LEVER OPERATOR ASSEMBLY

Harry J. Collins, Jr., Bayside, Wis., assignor to Cutler-Hammer, Inc., Milwaukee, Wis., a corporation of Delaware

Filed Jan. 8, 1962, Ser. No. 68,227

Term of patent 14 years

(Cl. D26—13)

FIGURE 1 is an isometric view of a lever operator assembly showing my new design;

FIG. 2 is an end view;

FIG. 3 is a side view the opposite side being a mirror image thereof;

FIG. 4 is a front view; and

FIG. 5 is the other end view.

I claim:

The ornamental design for a lever operator assembly, substantially as shown and described.
